COMBINED MAGNETIC TAPE RECORDER AND VIDEO MONITOR

Marvin A. Southcott, Palo Alto, Calif., assignor to Am-
pex Corporation, Redwood City, Calif., a corporation
of California

Filed Mar. 13, 1961, Ser. No. 64,268

Term of patent 14 years

(Cl. D26—14)

FIG. 1

Des. 192,361

PAGE 2

FIG. 2

FIG. 1

FIGURE 1 is a front perspective view of a combined magnetic tape recorder and video monitor showing my new design;

FIGURE 2 is a side elevational view of the design shown in FIGURE 1, the opposite side being substantially the same; and

FIGURE 3 is a rear elevational view of the design shown in FIGURE 2.

I claim:

The ornamental design for a combined magnetic tape recorder and video monitor, substantially as shown and described.
